Primary Examiner — Celia Murphy*Assistant Examiner* — Clare Ann Gannon(74) Attorney, Agent, or Firm — Fross Zelnick Lehrman & Zissu, P.C.; Lawrence E. Apolzon, Esq.(57) CLAIM

The ornamental design for footwear, as shown and described.

DESCRIPTION

FIG. 1 is a front perspective view of the footwear showing my new design;

FIG. 2 is a right side view thereof;

FIG. 3 is a front view thereof; and,

FIG. 4 is a rear view thereof.

The broken lines showing the heel, portions of the upper, and portions of the straps in the drawings show parts of the footwear that form no part of the claimed design.

1 Claim, 4 Drawing Sheets(56)
